Claims priority, application Germany Mar. 12, 1960

7 Claims. (Cl. 75—49)

The present invention relates to an apparatus for degassing liquids, and especially liquids of a low density, by the circulatory degassing method by means of a vacuum in which the respective liquids rise to a barometric height of several meters or more.

It is an object of the invention to provide an apparatus of the above-mentioned type which is adapted to reduce the actual height of rise of the liquid to be degassed considerably below the barometric height so that the entire degassing apparatus may be made of a considerably smaller size.

A further object of the invention is to provide such an apparatus which is also adapted to be used for degassing liquid materials of a high density, for example, molten steel, and for also reducing the height of rise of such liquids to a considerably lower level than the barometric height.

Thus, the new apparatus is designed to reduce, for example, the height of rise of molten steel in the evacuated degassing vessel from the normal full barometric height of approximately 1.40 m. to a height of only a few decimeters, so that the size of the entire degassing apparatus may be reduced accordingly. This advantage attained by the present invention is even more apparent if liquids of a low density are to be degassed, for example, plastics, or organic liquids such as mineral oils with a density of approximately 0.8 and a barometric height of approximately 12 m. The invention is, however, also applicable to metals such as aluminum with a density of 2.7 and a barometric ceiling of approximately 3.7 m.

The circulatory degassing method has been very frequently applied in recent times for the purpose of degassing steel by means of a vacuum. According to this method, a degassing vessel which is adapted to be evacuated is provided with a pair of substantially vertical, downwardly extending pipes, the ends of which are immersed from above into the molten steel which is to be degassed. A suitable conveying gas is then conducted into one of the pipes and, because of its considerably lower density, this gas will rise quickly within this pipe and thereby take along the liquid metal into the evacuated degassing vessel. Due to the vacuum in the degassing chamber of this vessel, the gases contained in the molten metal as well as the conveying gas are then extracted from the metal, and the degassed metal then flows through the second pipe back to its container in which it becomes mixed with the remainder of molten metal. The container of the metal generally consists of a casting ladle, the upper end of which is completely open so that the molten metal therein is under atmospheric pressure and covered merely by a layer of slag.

Since according to this method the liquid to be degassed, for example, the molten metal, is maintained in its container under a normal atmospheric pressure, it will rise in both pipes to a level in accordance with the differential pressure relative to the vacuum which is maintained in the degassing vessel. At a sufficient vacuum, the liquid will then rise in the pipes to the barometric height. Since the specific gravity of iron and also of steel alloys amounts approximately to 7.8, the barometric height thereof

2

amounts to approximately 1.4 m. Even though such an apparatus has still a relatively small size, it may in certain cases be still too large so that a reduction in size may be desirable or necessary.

If the circulating method as described is to be applied for the purpose of degassing other liquids which have a considerably lower density, the barometric height would be considerably higher and the required apparatus would therefore be very high. Also if liquids are to be degassed at a higher temperature or if they have a higher melting temperature, for example, aluminum, they would cool off excessively within the necessary long pipes leading from the liquid container to the degassing vessel.

These disadvantages will be overcome by applying the method according to the present invention. It constitutes a valuable improvement over the conventional circulatory degassing method, and this improvement is attained by closing the container for the liquid which is to be degassed by means of a cover and by evacuating it by means of a vacuum pump through a pipe leading into the container. The liquid to be degassed is therefore no longer maintained under a normal atmospheric pressure, but under a vacuum of a size which is dependent upon the size of the preliminary pump. A second vacuum pump is connected to the degassing vessel and produces therein a reduced pressure which is still lower than the vacuum which is produced by the first pump in the container above the surface of the liquid. This second pump for producing the necessary differential pressure is preferably a Roots-type pump. The height to which the liquid has to rise is therefore now dependent upon the differential pressure which is produced by the Roots-type pump between the reduced pressures in the liquid container and in the degassing vessel. In order to permit this height to be varied, the Roots-type pump may be provided either with a by-pass which contains a control valve which permits the differential pressure to be varied or the suction outlet of the liquid container may be connected to a control valve which likewise permits the height of rise to be varied. It is also possible to use both of these control means in combination with each other.

These objects, features, and advantages of the present invention will become more clearly apparent from the following detailed description of a preferred embodiment thereof as illustrated in the accompanying drawing.

The apparatus according to the invention consists of a container 2 which is closed by a cover 3 and holds the liquid 1 which is to be degassed. The liquid may be filled into the container through an inlet pipe 4 and may be discharged therefrom through an outlet pipe 6. A pair of pipes 8 and 9 extend upwardly through the cover 3 and their free lower ends are immersed into the liquid 1, while the upper ends are connected to the bottom of the degassing vessel 10. Pipe 8 serves as an inlet pipe for conducting the liquid into degassing vessel 10, and for this purpose a suitable conveying gas of a considerably lower density than the liquid to be degassed is conducted into pipe 8 through a pipe 11 so that this gas, while rising in pipe 8, will take along the liquid into the degassing vessel 10 in the direction as shown by arrow 12. After passing through vessel 10, the liquid flows out through pipe 9 and downwardly in the direction of arrow 13 into the main body of liquid 1 in container 2.

The chamber in container 2 above the surface of liquid 1 is evacuated through pipe 15 by means of a preliminary vacuum pump 16, while the degassing chamber in vessel 10 is evacuated by a Roots-type pump 19 through pipe 17 and through a vapor and dust separator 18. Thus, by means of the Roots-type pump 19, a differential pressure is established through the connecting pipe 15 between the degassing chamber 10 and the chamber in container 2 above the surface of liquid 1.

The height of rise of the liquid which is dependent upon the size of this differential pressure may in some cases be very great. In order to reduce this height, a by-pass 20 with a control valve 21 is provided by means of which the differential pressure may be regulated. If control valve 21 is fully opened, the result of the operation of pump 19 is practically no more than that the gases will be sucked up through by-pass 20. If valve 21 is, however, almost entirely closed, the differential pressure which is produced by the Roots-type pump 19 between the chamber in container 2 above the surface of liquid 1 and the inside of degassing vessel 10 will be only slightly reduced.

Instead of regulating the differential pressure by means of by-pass 20 and control valve 21, it is also possible to do this by means of a control valve 22 which is inserted into pipe 15. Especially it is possible to increase the differential pressure considerably by substantially closing valve 22 which will promote the liberation of gases from the liquid in container 2. In order to vary the rise of the liquid, so as either to increase or decrease it, it is advisable to provide both valves 21 and 22 and by-pass 20.

At the inside of degassing vessel 10, inclined guide plates 25 or the like are preferably mounted along which the liquid to be degassed may flow downwardly in the form of a thin layer and will therefore be exposed for a greater length of time to the vacuum within vessel 10. In some cases it may also be advisable to provide the upper end of inlet pipe 8 with a nozzle 26 so that the liquid to be degassed, for example, mineral oil, will be ejected into degassing vessel 10 in the form of a fountainlike spray. In order to prevent larger drops of liquid from entering into suction pipes 15 and 17, suitable baffles 30 or the like may also be provided in container 2 and vessel 10 in front of the openings into these pipes.

For controlling the apparatus, vacuum gauges 35 and 36 are provided for measuring the pressure in container 2 above the surface of liquid 1 and in the degassing vessel 10. Furthermore, in order to measure the differential pressure directly and for determining the exact height of rise of the liquid, it is also advisable to provide a differential pressure gauge which measures the difference in pressure between the two chambers.

Between line 11 and, for example, the connection between the differential pressure gauge and container 2 it is also possible to provide a pressure relief valve. Such a valve may also be used in place of or in addition to the control valve 21.

By providing a preliminary vacuum in container 2, the method according to the invention attains a preliminary degasification of the liquid before it passes through the degassing vessel 10, and this preliminary degasification will be rendered still more efficient by the continuous circulation of the liquid through the degassing vessel 10. The high vacuum in degassing vessel 10 serves so-to-speak as a second degassing stage in which the remainder of the gases contained in the liquid will be extracted therefrom.

Although my invention has been illustrated and described with reference to the preferred embodiments thereof, I wish to have it understood that it is in no way limited to the details of such embodiments, but is capable of numerous modifications within the scope of the appended claims.

One of these modifications may be mentioned especially. It consists in the use of a special and separate container for the liquid 1 to be degassed, so that in this case the container 2 is no longer used as a container for the liquid, but as a vacuum chamber in which the said special and separate container is to be placed. Such a container can be inserted into the evacuated chamber 2 or removed from it when the upper cover together with the degassing vessel 10 and the pipes 8 and 9 have been raised to a sufficient height. The special and separate container may be a ladle containing molten metal. As this

modification is only a very simple one and can be easily realized by everybody skilled in the art, it has not been shown by a drawing.

Having thus fully disclosed my invention, what I claim is:

1. In a continuous recycling method for vacuum degasification of molten metals and having as the steps of such method continuously passing molten metal from a molten metal zone upward in a confined stream and with the aid of a lifting gas into a vacuum degasification zone and continuously discharging treated molten metal from said vacuum degasification zone downwardly into said container zone into said molten metal zone below the level of the molten metal therein, and at a point external to and spaced apart from the point at which the molten metal is again continuously moved upward, the improvement which comprises in combination with said steps substantially maintaining a vacuum above the molten metal in said molten metal zone, and substantially maintaining a pressure differential between the vacuum in said degasification zone and the vacuum in said molten metal zone with the vacuum in said first mentioned zone being greater than in said last mentioned zone to thereby assure a barometric height for the discharging of the confined stream of molten metal, which is less than the normal barometric height thereof.

2. In a continuous recycling device for the vacuum degasification of molten metal and having as elements vacuum degassing chamber means, a lower positioned container for holding molten metal, riser conduit means for conveying molten metal from said container to said chamber means, discharge conduit means for discharging molten metal from said chamber into said container, means for forcing gas bubbles into and through said riser conduit means, said riser and said discharge conduit means being with their immersion ends arranged in nonconcentric separate and spaced relation, the improvement which comprises, in combination with said elements, such container in substantially closed form, means for evacuating the upper portion of said container and means for maintaining a differential vacuum between said degassing chamber means and said container with a greater evacuation for said chamber means.

3. An apparatus as defined in claim 2, in which said evacuating means comprise a first and second suction pump, a pipe connecting said container to the suction side of the first pump, and a pipe connecting said degassing chamber means to the suction side of the second pump, and means for connecting the pressure side of said second pump to the pipe connecting said container to the suction side of said first pump.

4. An apparatus as defined in claim 3, further comprising a control valve inserted into said pipe connecting said container to said first pump for varying the differential pressure produced by said pumps between said container and said degassing chamber means.

5. An apparatus as defined in claim 2, in which said evacuating means comprise a first and second suction pump, a pipe connecting said chamber to the suction side of the first pump, and a pipe connecting said degassing chamber means to the suction side of the second pump, a pipe connecting the suction sides of said two pumps to each other, and a control valve inserted in said last pipe for varying the differential pressure produced by said pumps between said container and said degassing chamber means.

6. An apparatus as defined in claim 2, further comprising guiding means within said degassing chamber means for receiving the liquid injected into said chamber means through one of said pipes and for guiding said liquid so as to flow in a thin layer in a downward direction along said guiding means.

7. An apparatus as defined in claim 2, further comprising nozzle-like means in said degassing chamber means on the end of said pipe into which said gas is inserted

for directing said liquid in a fountainlike spray into said chamber means.
